UNITED STATES PATENT OFFICE.

CHARLES A. A. RAND, OF CHICAGO, ILLINOIS, ASSIGNOR TO INTERNATIONAL HAR-
WESTER COMPANY, OF CHICAGO, ILLINOIS, A CORPORATION OF NEW JERSEY.

FEEDING MEANS FOR CENTRIFUGAL GRINDERS.

Application filed December 17, 1923. Serial No. 681,073.

The present invention relates to improvements in centrifugal grinders and has for its object to improve the efficiency of such machines, and more particularly of the feeding means employed therewith.

In the type of centrifugal grinders known as rotary hammer mills, the reduction of grain, forage, etc. is effected by pivoted hammers carried on a rotor which revolves at high speed above a perforated metal screen curved to conform to the circuit described by the hammers during rotation. The ground material is preferably discharged or drawn off and collected by a current of air drawn through the mill, and it is the object of this invention to insure entrance of the required supply of air to the grinding chamber and to make the entering air current take the path of the material being fed into the mill so that feeding is facilitated and there is no tendency for the material to choke or be thrown back.

A further object of the invention is to provide feeding means including a chute and an adjustable inlet gate or plate which afford a feed opening or throat that may be varied in size by adjusting the gate and to conduct the inflowing air by means of a conduit or duct on the gate to an opening or air port in the gate just above the feed throat and, therefore, always in the same relation to the material being fed, irrespective of the adjustment of the inlet gate.

With these main objects in view, the invention resides in the combination and arrangement of parts and details of construction, or the equivalents thereof, hereinafter more particularly described and claimed.

Referring to the accompanying drawing:

Fig. 1 is a plan view of a grinder with the novel feeding device attached;

Fig. 2 is a similar side view; and

Fig. 3 is a detailed view of the inner side of the inlet plate or gate.

The grinder with which the invention is combined may be of any preferred construction, and, in this instance, there is illustrated a grinder comprising a casing formed of a lower fixed section 10 and an upper section or dome 11 which is hinged to the lower section at 12 and is detachably secured thereto as by a pivoted bolt 13. The lower section 10 is composed of similar end plates which support the sheet metal hopper or bin

14 into which the ground material passes from the perforated metal screen 15 that is supported in any suitable manner on the end plates. The ground material is preferably drawn off from the receiving bin 14 through the discharge spout 16 by means of an exhaust fan in the usual manner. The upper section 11 is also composed of similar end plates which may be of cast metal and these are connected by a rear curved sheet metal plate secured to the end plates in any suitable way, and reinforced by a series of transverse rods 17 connecting the edges of the end plates. The lower part of the front of the upper section of the grinder casing is also formed by a curved plate reinforced by rods similar to those above described, and the relative curvatures of the front and rear plates of the grinder are such that their upper ends are spaced apart vertically leaving a feed inlet which is, in general, tangentially related to the rotor within the casing.

The rotor, which is shown in dotted lines in Fig. 2, is carried on a shaft 18 journaled in split bearings 19 formed in the respective edges of the upper and lower side plates 10 and 11. A driving pulley 20 is provided on the projecting end of the rotor shaft 18.

The grinder construction just described forms no part of the present invention except as it cooperates therewith, and the parts more directly related to the invention comprise a feed chute or conveyor 21 in the form

of an open trough which is pivotally connected at 22 at the lower edge of the feed inlet of the grinder and extends therefrom in a generally horizontal direction. At the upper edge of this inlet there is hingedly mounted a feed plate or gate 23 which ex-

ends over or covers the feed inlet and extends downwardly at an outward angle to a point adjacent the floor of the chute 21. Chute 21 is adjustably supported by brace bars 24 which, together with bars 25 engaging the sides of the chute, are attached at 26 to ears or lugs on the bottom of the chute 21.

The lower edge of the inlet gate 23 is supported by slotted arms 27 the upper portions of which are adjustable between clamp collars on a transverse rod 28 extending across the chute and connecting the upper ends of the bars 25. Wing nuts 29 are pivoted on the ends of rod 28 for clamping the supporting bars 27 at any desired adjustment. This provides means for adjusting the inlet gate

on its pivot and varying the size of the feed aperture or throat allowed between the lower edge of the gate and the bottom of the feed chute, as required for the particular material being fed to the grinder. It will be evident that this construction permits variation of the feeding opening as desired and that the unused area of the grinder inlet is always closed by the gate 23 and dust, etc., thereby confined. As the feeding throat allowed by the gate is usually closed by the material being fed therethrough during operation of the mill, it becomes necessary to provide for the entrance of the necessary supply of air. This is accomplished by providing the gate 23 with an opening 30 adjacent its lower edge. This opening is preferably a slot 30 extending parallel with the lower edge of the gate as shown in Fig. 3. The slot 30 opens into or communicates with an air duct or conduit on the outer face of the plate 23 and formed by a casing 31 secured thereon. The conduit 31 opens near the upper edge of the plate at 31^a where the air enters and is directed downwardly to the opening or slot 30, through which it passes, entering directly above and being directed in the path of the material being fed just beneath the lower edge of gate 23. In this manner the blast of entering air is caused to flow in the direction of travel of the material and assists the feeding operation as well as supplying the necessary amount of air to the grinder. It will be noticed that arrangement of the air port is such that it remains in practically the same relation to the material at all adjustments of the plate 23 and that the arrangement of the chute 21 and plate or gate 23 with relation to the inlet opening of the mill is such that escape of dust and such material as may be thrown back from the rotor will be effectively prevented.

While the construction above described exemplifies the preferred form of the invention, it is obvious that certain changes in details of construction may be made without departing from the scope of the invention as defined in the following claims.

50. What is claimed is:

1. An improvement in centrifugal grinders comprising a casing having a lateral feed opening, a trough shaped chute extending substantially horizontally from said casing for guiding material to said lateral feed opening, a gate pivotally mounted so as to extend within the said chute downwardly and outwardly with respect to said casing, the gate having an air port formed therein, a shield covering the port, and means for adjustably supporting the gate.
2. An improvement in centrifugal grinders comprising a casing having a lateral feed opening near the top thereof, a trough shaped chute extending substantially hori-

zontally from the top of the casing so as to guide material to the lateral feed opening, a gate pivotally mounted with respect to the top of the casing and extending outwardly and downwardly therefrom within the chute, the gate being so positioned that its lower edge is adjacent the floor of the chute, a casing secured to the gate so as to form an air passage therewith, and means for supporting the gate within the chute including means for adjusting the gate on its pivot.

3. The combination with a grinder casing having a lateral feed opening, of a trough shaped chute extending therefrom and a gate covering said opening and having its lower edge adjacent the floor of the chute, said gate having an opening near its lower edge and being provided with an air conduit on its outer side extending from a higher point on the gate down to said opening.

4. The combination with a grinder casing having a lateral feed opening, of a trough shaped chute extending therefrom and a gate for said opening consisting of a plate adjustably pivoted at the upper edge of the opening and extending at an outward angle to a point adjacent the floor of the chute, said plate being provided with an air opening near its lower edge.

5. The combination with a grinder casing having a lateral feed opening, of a trough shaped chute extending therefrom, a gate for said opening consisting of a plate pivoted at the upper edge of said opening and extending at an outward angle to a point adjacent the floor of the chute, said plate having a transverse slot near its lower edge and being provided with an air conduit on its outer side extending from a higher point on the plate down to said slot, and adjustable supporting means connected to the lower part of the plate.

6. The combination with a material treating device having pneumatic discharging means, a chute of feeding means comprising an adjustable gate hinged at the inlet of the device, and means for supporting the gate so that it extends downwardly within the chute, said gate being provided with a hooded air inlet port at a point adjacent the feed opening allowed beneath the lower edge of the gate.

7. An improvement in comminuting machines comprising, in combination, a material treating device, a casing substantially enclosing said device, a chute for directing material toward the device, an adjustable gate mounted in the chute in proximity to the inlet of the casing for preventing the escape of material which has been acted upon by the device, the gate being formed with an air port for allowing the passage of air through the machine along with the material acted upon, and a shield covering

the port and preventing the passage of material to be comminuted through the port.

8. An improvement in a feeding device for a mill comprising, in combination, material directing means for guiding material toward the mill, a movable gate in said means and located adjacent the mill for preventing the escape of material which has been acted upon by the mill, said gate being 10 formed with a port allowing the passage of

air through the mill along with the material acted upon by the mill, and a member secured to the gate so as to cover said port and prevent the passage of material through the port toward the mill, said member being 15 spaced from the gate and forming an air passage-way between itself and the gate.

In testimony whereof I affix my signature.

CHARLES A. A. RAND.
